CLAIM

The ornamental design for a single-pole breaker lockout, as shown and described.

DESCRIPTION

FIG. 1 is an isometric view of a top, front, and right side of an ornamental design for a single-pole breaker lockout;

FIG. 2 is an isometric view of a bottom, rear, and left side of the single-pole breaker lockout of FIG. 1;

FIG. 3 is a front elevational view of the single-pole breaker lockout of FIG. 1;

FIG. 4 is a rear elevational view of the single-pole breaker lockout of FIG. 1;

FIG. 5 is a right side elevational view of the single-pole breaker lockout of FIG. 1;

FIG. 6 is a left side elevational view of the single-pole breaker lockout of FIG. 1;

FIG. 7 is a top plan elevational view of the single-pole breaker lockout of FIG. 1; and,

FIG. 8 is a bottom plan elevational view of the single-pole breaker lockout of FIG. 1.

The dash-dash broken lines are included for the purpose of illustrating portions of the single-pole breaker lockout that form no part of the claimed design. The dot-dash broken lines are included for the purposes of illustrating a boundary line that forms no part of the claimed design.

In a preferred embodiment, the nature of this product is as a locking device for isolating or limiting access to controls, such as switches or breakers.
